UNITED STATES PATENT OFFICE

102,811

DESIGN FOR A WRIST RADIO CASING

Norwood Anderson, Chester, N. Y.

Application October 31, 1936, Serial No. 65,629

Term of patent 3½ years

To all whom it may concern:

Be it known that I, Norwood Anderson, a citizen of the United States, residing at Chester, in the county of Orange and State of New York, have invented a new, original, and ornamental Design for a Wrist Radio Casing, of which the following is a specification, reference being had to the accompanying drawing, forming part thereof.

In the drawing:

Figure I is a top view of a wrist radio casing, showing my new design.

Fig. II is a side view of the wrist radio casing.

I claim:

The ornamental design for a wrist radio casing as shown.

NORWOOD ANDERSON.
